(57) **ABSTRACT**

A flower hydrating transport pouch device for cost efficiently preserving fresh cut flowers during transport from a point of sale includes a pouch defining an interior space. The pouch has a pair of lateral sides and an upper edge. The upper edge is removable from a body of the pouch to expose an opening into the interior space. A hydrating fluid is in the interior space. A closure is positioned on the body of the pouch adjacent to the opening for selectively closing the opening. A tether line extends from the pouch for engaging interior structure of a vehicle for transporting flowers having stems extending into the hydrating fluid within the interior space of the pouch.

BACKGROUND OF THE INVENTION

(1) Field of the Invention

The disclosure relates to fluid holding pouch devices and more particularly pertains to a new fluid holding pouch device for cost efficiently preserving fresh cut flowers during transport from a point of sale.

(2) Description of Related Art including
information disclosed under 37 CFR 1.97 and 1.98

The prior art relates to fluid holding pouch devices. Known prior art lacks a self contained receptacle to resist tipping during transport which is also cost efficient for preserving fresh cut flowers during transport from a point of sale.

BRIEF SUMMARY OF THE INVENTION

An embodiment of the disclosure meets the needs presented above by generally comprising a pouch defining an interior space. The pouch has a pair of lateral sides and an upper edge. The upper edge is removable from a body of the pouch to expose an opening into the interior space. A hydrating fluid is in the interior space. A closure is positioned on the body of the pouch adjacent to the opening for selectively closing the opening. A tether line extends from the pouch for engaging interior structure of a vehicle for transporting flowers having stems extending into the hydrating fluid within the interior space of the pouch.

There has thus been outlined, rather broadly, the more important features of the disclosure in order that the detailed description thereof that follows may be better understood,

2

and in order that the present contribution to the art may be better appreciated. There are additional features of the disclosure that will be described hereinafter and which will form the subject matter of the claims appended hereto.

5 The objects of the disclosure, along with the various features of novelty which characterize the disclosure, are pointed out with particularity in the claims annexed to and forming a part of this disclosure.

10 BRIEF DESCRIPTION OF SEVERAL VIEWS OF
THE DRAWING(S)

The disclosure will be better understood and objects other than those set forth above will become apparent when 15 consideration is given to the following detailed description thereof. Such description makes reference to the annexed drawings wherein:

FIG. 1 is a front view of a flower hydrating transport pouch device according to an embodiment of the disclosure.

20 FIG. 2 is a top front side perspective view of an embodiment of the disclosure.

FIG. 3 is a top view of an embodiment of the disclosure.

FIG. 4 is a side view of an embodiment of the disclosure.

FIG. 5 is a front view of an embodiment of the disclosure

25 in use.

FIG. 6 is a front view of an embodiment of the disclosure in use.

FIG. 7 is a front view of an embodiment of the disclosure.

FIG. 8 is a rear view of an embodiment of the disclosure.

30 DETAILED DESCRIPTION OF THE
INVENTION

With reference now to the drawings, and in particular to 35 FIGS. 1 through 8 thereof, a new fluid holding pouch device embodying the principles and concepts of an embodiment of the disclosure and generally designated by the reference numeral 10 will be described.

As best illustrated in FIGS. 1 through 8, the flower 40 hydrating transport pouch device 10 generally comprises a pouch 12. The pouch 12 defines an interior space 14 to receive and hold fresh cut flowers 16. The pouch can be made of polyethylene terephthalate (PET), polyethylene (PE), and an extruded film made from polypropylene (MOPP). The pouch 12 has a pair of lateral sides 18. The pouch 12 has a bottom side 20. The bottom side 20 is planar wherein the pouch 12 is configured for standing upright on a support surface such as the bottom of a cup holder in a vehicle or any other substantially horizontal surface. The bottom side 20 has a front edge 22 and a rear edge 24.

50 Respective medial sections 26 of the front edge 22 and the rear edge 24 are covexly arcuate. The pouch 12 is generally symmetrical such that determination of the front edge 22 and rear edge 24 are mirror images of each other. The pouch 12 has a medial portion 28 between the lateral sides 18. The medial portion 28 extends upwardly from the medial sections 26 of the front edge 22 and the rear edge 24. The medial portion 28 flares outwardly extending away from the bottom side 20 of the pouch 12.

55 An upper edge 30 of the pouch 12 is removable from a body 32 of the pouch 12 to expose an opening 34 into the interior space 14. A hydrating fluid 36 is positioned in the interior space 14 and enclosed within the pouch 12 prior to removal of the upper edge 30. The hydrating fluid 36 may be 60 water alone or a mixture of water and plant nutrients dissolved into water. It is contemplated the plant nutrients would be those known to persons skilled in the art and

currently provided in a packet at the time of purchase for addition to water when placing fresh cut flowers into a vase or other receptacle at a final display destination.

A closure **38** is coupled to the pouch **12**. The closure **38** may be a zipper resealable press to seal closure. The closure **38** is positioned on the body **32** of the pouch **12** adjacent to the opening **34**. The closure **38** selectively closes the opening **34** when desired. The closure **38** may be provided with a conventional enhanced seal holding the closure in a sealed condition until after the upper edge **30** is removed and a user initially opens the closure **38**.

A tether line **40** is coupled to the pouch **12** facilitating holding of the pouch **12** in an upright position to inhibit tipping or spillage. The tether line **40** extends from the pouch **12** such that the tether line **40** is configured for engaging interior structure **42** of a vehicle **44**. Thus, the pouch **12** is configured for transporting flowers having stems extending into the hydrating fluid **36** within the interior space **14** of the pouch **12**. A toggle **66** may be coupled to the tether line **40** wherein the toggle **66** is configured for forming the tether line **40** into an adjustable sized loop **46** extending from the pouch **12**. Thus, the tether line **40** can be used to hang the pouch **12** from a seat back, hook, or similar structure in the vehicle **44**. The toggle **66** has a locking element **48** biased into engagement with the tether line **40** for fixing a position of the toggle **66** on the tether line **40**. The locking element **48** is manipulatable to release the locking element **48** from the tether line **40** for adjustment of a position of the toggle **66** on the tether line **40**. Alternatively, the tether line **40** may also be simply tied into a loop or otherwise secured by a clip or other binder sufficient to hold the tether line **40** in the loop **46** without becoming disengaged from the interior structure **42** of the vehicle **44**. It is also contemplated that the tether line **40** may be used to hang or engage the pouch **12** to any supporting structure other than inside the vehicle **44** if so desired. The pouch **12** is also sized similar to conventional sizes of travel cups or bottles to be positionable within a cup holder **50** in the vehicle **44**. It is also contemplated that the tether line **40** may be formed integrally with the structure of the pouch **12** and set off by perforations to allow for the tether line **40** to be separated along the perforations forming a single piece or two pieces extending from the pouch **12**.

The pouch **12** may have a pair of notches **52** extending into a respective one of the lateral sides **18** of the pouch **12**. Each notch **52** is configured to facilitate tearing of the pouch **12** between the closure **38** and the upper edge **30** for removal of the upper edge **30** to expose the opening **34**.

Indicia **54** may be positioned on the pouch **12**. The indicia **54** may be related to an occasion or event such as an anniversary, birthday, holiday, or any occasion when it may be common to purchase flowers as a gift or decorative display.

In an embodiment shown in FIGS. 1 through 6, the flower hydrating transport pouch device **10** includes a pair of tabs **56**. Each of the tabs **56** extends from a respective one of the lateral sides **18** of the pouch **12**. Each of the tabs **56** may be triangular having a straight upper edge **58** oriented perpendicular to the respective lateral side **18** of the pouch **12**. The straight upper edge **58** may also be parallel to the opening **34**. Each of a pair of tab apertures **68** extends through a respective one of the tabs **56**. The tether line **40** is threaded through the tab apertures **68** in the tabs **56**.

In an embodiment shown in FIGS. 7 and 8, the flower hydrating transport pouch device **10** includes a pair of pouch apertures **60** extending through the pouch **12**. Each of the pouch apertures **60** is positioned adjacent to a respective one of the lateral sides **18** of the pouch **12** and is positioned

between the closure **38** and the upper edge **30**. The tether line **40** is threaded through the pouch apertures **60**. Although shown in the embodiment of FIGS. 7 and 8, a display hole **62** may be provided in either embodiment extending through the pouch **12**. The display hole **62** is positioned adjacent to the upper edge **30** and between the upper edge **30** and the closure **38**. The display hole **62** is configured for hanging the pouch **12** on a display hook or the like at a point of sale display.

In use, the pouch **12** is made available for purchase where fresh cut flowers or flower arrangements may be purchased. The pouch **12** is opened and flowers inserted so that the hydrating fluid **36** is accessible to the fresh cut flowers or arrangement. This facilitates preservation of the flowers and prevents wilting or premature drying of the flowers during transport from the point of sale. This allows flowers to be bought and preserved at less expense than purchasing a vase and with less concern or need to rush to a destination where the flowers can be placed into a more permanent receptacle such as a vase.

With respect to the above description then, it is to be realized that the optimum dimensional relationships for the parts of an embodiment enabled by the disclosure, to include variations in size, materials, shape, form, function and manner of operation, assembly and use, are deemed readily apparent and obvious to one skilled in the art, and all equivalent relationships to those illustrated in the drawings and described in the specification are intended to be encompassed by an embodiment of the disclosure.

Therefore, the foregoing is considered as illustrative only of the principles of the disclosure. Further, since numerous modifications and changes will readily occur to those skilled in the art, it is not desired to limit the disclosure to the exact construction and operation shown and described, and accordingly, all suitable modifications and equivalents may be resorted to, falling within the scope of the disclosure. In this patent document, the word "comprising" is used in its non-limiting sense to mean that items following the word are included, but items not specifically mentioned are not excluded. A reference to an element by the indefinite article "a" does not exclude the possibility that more than one of the element is present, unless the context clearly requires that there be only one of the elements.

I claim:

1. A flower hydrating transport pouch device comprising: a pouch, said pouch defining an interior space, said pouch having a pair of lateral sides; an upper edge of said pouch being removable from a body of said pouch wherein removal of said upper edge exposes an opening into said interior space wherein said pouch is configured to receive flowers having stems inserted into said pouch; a hydrating fluid positioned in said interior space, said hydrating fluid being a mixture of water and plant nutrients wherein said hydrating fluid is configured for hydrating the flowers having the stems inserted into said pouch; a closure coupled to said pouch, said closure being positioned on said body of said pouch adjacent to said opening, said closure selectively closing said opening.
2. The flower hydrating transport pouch device of claim 1, further comprising: a tether line, said tether line being coupled to said pouch, said tether line extending from said pouch such that said tether line is configured for engaging interior structure of a vehicle whereby said pouch is configured

5

for transporting the flowers having the stems extending into said hydrating fluid within said interior space of said pouch;
 a pair of tabs, each of said tabs extending from a respective one of said lateral sides of said pouch; and
 a pair of tab apertures, each of said tab apertures extending through a respective one of said tabs, said tether line being threaded through said tab apertures in said tabs.

3. The flower hydrating transport pouch device of claim 2, further comprising each of said tabs being triangular.

4. The flower hydrating transport pouch device of claim 3, further comprising each tab having a straight upper edge oriented perpendicular to said respective lateral side of said pouch.

5. The flower hydrating transport pouch device of claim 4, further comprising said straight upper edge being parallel to said opening.

6. The flower hydrating transport pouch device of claim 2, further comprising a toggle coupled to said tether line wherein said toggle is configured for forming said tether line into an adjustable sized loop extending from said pouch.

7. The flower hydrating transport pouch device of claim 6, further comprising said toggle having a locking element, said locking element being biased into engagement with said tether line for fixing a position of said toggle on said tether line, said locking element being manipulatable to release said locking element from said tether line for adjustment of a position of said toggle on said tether line.

8. The flower hydrating transport pouch device of claim 1, further comprising a pair of notches, each of said notches extending into a respective one of said lateral sides of said pouch wherein each notch is configured to facilitate tearing of said pouch between said closure and said upper edge for removal of said upper edge to expose said opening.

9. The flower hydrating transport pouch device of claim 1, further comprising said pouch having a bottom side, said bottom side being planar wherein said pouch is configured for standing upright on a support surface.

10. The flower hydrating transport pouch device of claim 9, further comprising said bottom side having a front edge and a rear edge, respective medial sections of said front edge and said rear edge being covelexly arcuate.

11. The flower hydrating transport pouch device of claim 10, further comprising said pouch having a medial portion between said lateral sides, said medial portion extending upwardly from said medial sections of said front edge of said bottom side and said rear edge of said bottom side, said medial portion flaring outwardly extending away from said bottom side of said pouch.

12. The flower hydrating transport pouch device of claim 1, further comprising indicia positioned on said pouch, said indicia being related to an occasion or event.

13. The flower hydrating transport pouch device of claim 1, further comprising a display hole extending through said pouch, said display hole being positioned adjacent to said upper edge wherein said display hole is configured for hanging said pouch on a display hook.

14. A flower hydrating transport pouch device comprising:
 a pouch, said pouch defining an interior space, said pouch having a pair of lateral sides, said pouch having a

6

bottom side, said bottom side being planar wherein said pouch is configured for standing upright on a support surface, said bottom side having a front edge and a rear edge, respective medial sections of said front edge and said rear edge being covelexly arcuate, said pouch having a medial portion between said lateral sides, said medial portion extending upwardly from said medial sections of said front edge and said rear edge, said medial portion flaring outwardly extending away from said bottom side of said pouch;

an upper edge of said pouch being removable from a body of said pouch wherein removal of said upper edge exposes an opening into said interior space;

a hydrating fluid positioned in said interior space, said hydrating fluid being a mixture of water and plant nutrients;

a closure coupled to said pouch, said closure being positioned on said body of said pouch adjacent to said opening, said closure selectively closing said opening; and

a tether line, said tether line being coupled to said pouch, said tether line extending from said pouch such that said tether line is configured for engaging interior structure of a vehicle whereby said pouch is configured for transporting flowers having stems extending into said hydrating fluid within said interior space of said pouch;

a toggle coupled to said tether line wherein said toggle is configured for forming said tether line into an adjustable sized loop extending from said pouch, said toggle having a locking element, said locking element being biased into engagement with said tether line for fixing a position of said toggle on said tether line, said locking element being manipulatable to release said locking element from said tether line for adjustment of a position of said toggle on said tether line;

a pair of notches, each of said notches extending into a respective one of said lateral sides of said pouch wherein each notch is configured to facilitate tearing of said pouch between said closure and said upper edge for removal of said upper edge to expose said opening; and

indicia positioned on said pouch, said indicia being related to an occasion or event.

15. The flower hydrating transport pouch device of claim 14, further comprising:

a pair of tabs, each of said tabs extending from a respective one of said lateral sides of said pouch, each of said tabs being triangular, each tab having a straight upper edge oriented perpendicular to said respective lateral side of said pouch, said straight upper edge being parallel to said opening; and

a pair of tab apertures, each of said tab apertures extending through a respective one of said tabs, said tether line being threaded through said tab apertures in said tabs.

16. The flower hydrating transport pouch device of claim 14, further comprising a display hole extending through said pouch, said display hole being positioned adjacent to said upper edge wherein said display hole is configured for hanging said pouch on a display hook.
